US0D1022095S

(12) **United States Design Patent** (10) Patent No.: **US D1,022,095 S**
(45) Date of Patent: ** Apr. 9, 2024

(54) **GOLF CLUB GRIP**(71) Applicant: **PARSONS XTREME GOLF, LLC**,
Scottsdale, AZ (US)(72) Inventors: **Daniel C. Kirtley**, Scottsdale, AZ (US);
Raymond C. Gresalfi, Oyster Bay
Cove, NY (US)(73) Assignee: **PARSONS XTREME GOLF, LLC**,
Scottsdale, AZ (US)(**) Term: **15 Years**(21) Appl. No.: **29/845,747**(22) Filed: **Jul. 11, 2022**(51) LOC (14) Cl. ..... **21-02**(52) U.S. Cl.
USPC ..... **D21/756**(58) **Field of Classification Search**USPC **D21/756-758**
CPC A63B 60/06-60/34; A63B 60/00; A63B
60/46; A63B 59/60-59/80; A63B
49/00-49/14; A63B 53/14

CLAIM

The ornamental design for a golf club grip, as shown and described.

DESCRIPTION

FIG. 1 is a top perspective view of a golf club grip according to a first embodiment;

FIG. 2 is a bottom perspective view of the golf club grip of FIG. 1;

FIG. 3 is a front elevational view of the golf club grip of FIG. 1;

FIG. 4 is a rear elevational view of the golf club grip of FIG. 1;

FIG. 5 is a top view of the golf club grip of FIG. 1;

FIG. 6 is a bottom view of the golf club grip of FIG. 1;

FIG. 7 is a left side view of the golf club grip of FIG. 1;

FIG. 8 is a right side view of the golf club grip of FIG. 1;

FIG. 9 is a top perspective view of a golf club grip according to a second embodiment;

FIG. 10 is a bottom perspective view of the golf club grip of FIG. 9;

FIG. 11 is a front elevational view of the golf club grip of FIG. 9;

FIG. 12 is a rear elevational view of the golf club grip of FIG. 9;

FIG. 13 is a top view of the golf club grip of FIG. 9;

FIG. 14 is a bottom view of the golf club grip of FIG. 9;

FIG. 15 is a left side view of the golf club grip of FIG. 9;

FIG. 16 is a right side view of the golf club grip of FIG. 9;

FIG. 17 is a top perspective view of a golf club grip according to a third embodiment;

FIG. 18 is a bottom perspective view of the golf club grip of FIG. 17;

FIG. 19 is a front elevational view of the golf club grip of FIG. 17;

FIG. 20 is a rear elevational view of the golf club grip of FIG. 17;

FIG. 21 is a top view of the golf club grip of FIG. 17;

FIG. 22 is a bottom view of the golf club grip of FIG. 17;

FIG. 23 is a left side view of the golf club grip of FIG. 17; and,

FIG. 24 is a right side view of the golf club grip of FIG. 17.
